Des. 241,561
Patented Sept. 21, 1976

241,561

CHILD'S SWING AND SUPPORT FRAME ASSEMBLY OR SIMILAR ARTICLES

William R. Tomalinas, Jr., Wapwallopen, Pa., assignor to
Roth American, Inc., Wilkes-Barre, Pa.

Filed Mar. 12, 1975, Ser. No. 557,518

Term of patent 14 years

Int. Cl. D21—03

U.S. Cl. D34—5 M

FIG. 1.

FIG. 3.

FIG. 2.

FIG. 1 is a perspective view of a child's swing and support frame assembly or similar article showing my new design;

FIG. 2 is a side elevation thereof from the right side, the left side being a mirror image thereof; and

FIG. 3 is a front elevation thereof, the opposite view being the same except for a posterior elevation of the swing portion.

I claim:

The ornamental design for a child's swing and support frame assembly or similar articles, substantially as shown and described.
